United States Patent Office

Des. 200,565
Patented Mar. 9, 1965

200,565

FIRE HYDRANT

Herman E. Jackson, Decatur, Ill., assignor to Mueller Co.,
Decatur, Ill., a corporation of Illinois

Filed Mar. 1, 1963, Ser. No. 73,776

Term of patent 14 years

(Cl. D91—3)

Fig. 1

Fig. 2

Fig. 3

FIGURE 1 is a perspective view of one side of a fire hydrant embodying my new design, and

FIGURE 2 is a perspective view of the opposite side thereof.

FIGURE 3 is a fragmentary side elevational view thereof.

The dominant features of my design reside in the portions shown in full lines.

I claim:

The ornamental design for a fire hydrant, as shown and described.
